Patented Jan. 5, 1915.

UNITED STATES PATENT OFFICE.

EDWARD A. UNVERSAW AND ALBERT H. UNVERSAW, OF INDIANAPOLIS, INDIANA.

COVER FOR BUCKETS AND PAILS.

1,123,432.

Specification of Letters Patent.

Patented Jan. 5, 1915.

Application filed May 12, 1914. Serial No. 838,022.

To all whom it may concern:

Be it known that we, EDWARD A. UNVERSAW and ALBERT H. UNVERSAW, citizens of the United States, residing at Indianapolis, 5 in the county of Marion and State of Indiana, have invented certain new and useful Improvements in Covers for Buckets and Pails, of which the following is a specification.

10 This invention relates to covers for containers, such as candy, butter, lard buckets, and the like. These commodities are generally placed upon the retail market today in tin buckets of prescribed capacities, and 15 these buckets are provided upon their outer surfaces with suitable and expensive lithographed labels for displaying the names of the contents and of the manufacturers. It is particularly true in confining butter and 20 lard in these containers, that during the summer months the contents becomes melted and seeps out beneath the lids of the buckets in sufficient quantities to necessitate extra wrapping of the buckets so as 25 to prevent the purchasers' clothes from being soiled.

The object of the above invention is to provide an inexpensive and neat covering for the class of buckets above referred to, 30 which coverings are readily placed upon the buckets at the time of purchase so that the purchaser's clothes is prevented from coming into direct contact with any grease that may have collected upon the outer surfaces 35 of the buckets.

A further object of the invention is to provide a suitable and inexpensive covering for the class of buckets above referred to, which coverings may be easily and securely 40 attached to the buckets, the coverings moreover affording ample space for the desired advertising matter, so that the expense attached to the more expensive labels now in common use is eliminated.

45 We accomplish the above objects of our invention, by means of the construction illustrated in the accompanying drawings, in which—

Figure 1 is a top or plan view of one of our 50 improved covers for buckets, the same being shown flat as it appears when stamped from the stock and before the ends are secured together. Fig. 2 is a perspective view of a cover, the free ends of which have been attached, and which is ready to receive a bucket. Fig. 3 is a perspective view of one

of our improved covers in operative position upon a bucket. Fig. 4 is a fragmentary detail view in side elevation of a common and well known style of bucket showing the 60 means for holding our cover in position. Fig. 5 is a modified construction of a portion of the cover, adapted to form the top thereof.

Referring to the drawings, 10 represents 65 the main body of the cover which is preferably die cut from a suitable grade of paper, and 11 is a member that covers the top of the bucket when the bucket-cover is in operative position. In order that these covers 70 can be manufactured in large quantities and sold cheaply, these covers are cut from the paper stock by means of suitable dies. At the same operation in which the cover is 75 cut from the paper stock the cover is provided with the two apertures 12, and the slit 13 running from the margin of the cover to the openings 12. The cover is also provided with a slot 15, and a corresponding slot 16 is cut into the member 11, the latter also being 80 provided with a tongue 17. Before the free ends of the cover are secured together with glue or fastening devices, suitable printing can be placed upon said cover to indicate the contents, and the name and 85 place of manufacture. This saves the more expensive labels that are now employed on this class of buckets and pails.

Lard and butter buckets are made after a certain style well known to the trade, one 90 of the distinctive features being a semi-spherical hollow shell 20 being soldered to the opposite sides of the buckets, these shells being provided with suitable apertures to receive the hooked ends of the bails or handles 95 21. These semi-spherical hollow shells 20 perform an additional service in that they enable us to readily secure our covers 10 and prevent them from being accidentally displaced. When one of the covers is opened, 100 as shown in Fig. 2, a bucket is dropped into the cover, the semi-spherical shells 20 passing down through the slits 13 and into the apertures 12, the paper stock between the 105 apertures and the top edge of the covers along said slits spring back into position, the stock having sufficient strength to hold the covers in position. The member 11 is then bent down over the top of the bucket and the tongue 17 is then passed from within 110 through the slot 15 then bent upward and backward over the member 11 where the

free end of the tongue is held by inserting it through the slot 16, the end of the tongue being held between the member 11 and the bucket top.

- 5 In case there would be too great a loss in the stock by cutting the covers with the members 11 attached, the members 11 could be omitted and these could be cut separately, in which instance they would be provided 10 with an ear 25 whereby they may be attached to the covers by glue or metal fasteners of any preferred type.

From the above it will be seen that we have produced an inexpensive, neat and attractive cover for buckets and pails, whereby the same are wrapped so as to present a neat package, and whereby the purchasers' clothes may be protected against injury from the collection of any part of the contents that may leak out from the said buckets and pails.

While we have described our invention with more or less minuteness as regards details of construction and arrangement, and 25 as being embodied in certain precise forms, we do not desire to be limited thereto unduly or any more than is pointed out in the claims. On the contrary, we contemplate all proper changes in form, construction, and 30 arrangement, the omission of immaterial elements, and the substitution of equivalents, as circumstances may suggest or necessity render expedient.

Having thus fully described our said invention, what we desire to secure by Letters Patent, is:

- 35 1. A cover for buckets formed of a single piece of material having apertures for retaining said cover on the bucket, the said 40 cover being slitted to render the apertures

accessible, said cover having an integrally formed lid depending from its upper edge and said lid having a tongue depending from its marginal edge for securing said lid to the cover.

45 2. A cover for buckets formed of a single piece of material having apertures for retaining said cover on the bucket, the said 50 cover being slitted to render the apertures accessible, said cover being further provided with an elongated slot adapted to receive the fastening tongue, and said cover having 55 an integrally formed lid depending from its upper edge provided with an elongated slot adapted to receive the fastening tongue, and a fastening tongue depending from the 60 marginal edge of said lid and adapted to be passed through the elongated slots in the cover and lid for securing the latter to the former.

65 3. A cover for buckets formed of a single piece of material having apertures for retaining the said cover on the bucket, said 70 cover being slitted to render the apertures accessible, and a detached lid formed independently of the cover and having an integral portion forming an ear for attaching said lid to the cover, and being further provided with an integral portion forming a tongue for temporarily securing said lid to the cover.

In witness whereof, we have hereunto set our hands and seals at Indianapolis, Indiana, this 22nd day of April, A. D. one thousand nine hundred and fourteen.

EDWARD A. UNVERSAW. [L. s.]
ALBERT H. UNVERSAW. [L. s.]
